UNITED STATES PATENT OFFICE

170,288

TOY AIRPLANE

Joseph Edric Rylands, Lancashire, England

Application August 1, 1952, Serial No. 20,870
In Great Britain April 25, 1952

Term of patent 7 years

(Cl. D34—15)

To all whom it may concern:

Be it known that I, Joseph Edric Rylands, a British subject, residing at Lancashire, England, have invented a new, original, and ornamental Design for a Toy Airplane, of which the following is a specification, reference being had to the accompanying drawing, forming part thereof.

Fig. 1 is a front elevation view of a toy airplane, showing my new design; and Fig. 2 is a top plan view thereof.

I claim:

The ornamental design for a toy airplane, as shown.

JOSEPH EDRIC RYLANDS.
